UNITED STATES PATENT OFFICE.

RAYMOND E. CRANE, OF KITTANNING, PENNSYLVANIA.

SANITARY FIXTURE.

Application filed August 23, 1927. Serial No. 214,848.

My invention relates principally to urinals of the type where the fixture is ground in the rear to fit against a wall and which is either hung on the wall or placed against the wall and set on the floor and which is ordinarily used independently of the ordinary marble stalls. The larger fixtures of this type are ordinarily made of refractory clays of unsuitable density to properly combine with the best glazes.

The objects sought after in my invention are to produce a fixture of this type that will be large enough in area to make it unnecessary to use separate marble stalls and also large enough to provide an installation which will be sanitary in every way and at the same time of such design that it can be made of the higher qualities of vitreous china which are so dense in their body that the body and glaze will harmonize and insure against crazing which is so common with the coarser fixtures of this type now very largely used.

A large fixture of this type when made of vitreous china has a tendency to shrink and warp to such an extent that it is unsalable. There are also strains set up in the shrinkage of a large piece of this type that make the hazard of manufacturing during the firing operation extremely serious, so much so, in fact, that very few manufacturers are willing to attempt to manufacture such a difficult piece.

I have improved the method of manufacture of these fixtures in the manner shown in the accompanying drawings so that we are able to manufacture these fixtures on a commercial scale without a prohibitive loss or warpage.

The primary idea of the invention is the provision of triangular tubular columns extending the vertical length of the urinal on each side, thus supporting the fixture in such way that it will resist the strain incidental to the firing operation.

The accompanying drawings illustrate the method by which these objects are obtained. Figure 1 illustrates a front view in perspective of a urinal of this type. Figure 2 illustrates a view in side elevation. Figure 3 shows a top plan view of the same urinal as shown in Figures 1 and 2 indicating in dotted lines the location of the tubular columns which are an essential part of this invention. Figure 4 shows a view in perspective of the rear of the urinal il-

lustrating not only the back but the underside and one of the side walls. Down the center of the back of this urinal is illustrated a reinforcing flange construction for the fixture in addition to the tubular supporting columns as clearly indicated in Fig. 4. Figure 5 is a view indicating a manner in which this construction can be applied to a bath tub or other sanitary receptacle of this type, said view illustrating a portion of a tub showing a hollow roll rim at the top and the two triangular longitudinal members adapted to extend the length of the bottom of the tub on each side.

Similar figures refer to similar parts throughout the various views.

Referring to Figures 1, 2, 3 and 4, the back or main wall of the stall urinal (1) is made completely integral with the side walls, bottom and top, the side walls being furnished with a lip (2) which prevents splashing of the supply flushing stream. The flushing water is supplied through the inlet opening (5) from which it flows through the hollow supply chamber (3) out through flushing rim openings (4) in such manner as to thoroughly wash the rear wall (1) from whence the flushing water flows through the outlet opening (7) into the waste lines to which the fixture is to be connected. The construction of the bottom portion of the urinal as indicated at 6 is so designed as to prevent excess water of any kind splashing on the floor of the room.

It will be noted in these drawings that longitudinal hollow tubular chambers are formed by the rear or main wall (1), the side walls and the intermediate walls (8). The longitudinal hollow chambers form extremely strong supporting means which brace the fixture against drying and shrinkage strains and make the firing of the device much more feasible than otherwise. The tendency of this fixture during the firing operation, not provided with these tubular portions, would be for the side walls to shrink inwardly and for the back and side walls of the fixture to warp so that it could not be fit snugly against a wall.

Referring to Figure 5, the bottom of the bath tub (20) is made integral with the ends (21) and the sides (22). This fixture is also provided with an integral rim (23) and with similar tubular supports along the length of the fixture, as indicated at 24. This longitudinal tubular channel in the

case of a bath tub is horizontal where in the urinal it is vertical but the purpose of the construction and the manner in which it serves its purpose of resisting the strains incidental to drying and firing are the same as in the urinal.

Rib (9) is provided if desired to further prevent the rear wall from becoming distorted in the firing operation. In this way 10 this wall is supported at three points longitudinally so as to make a very much improved method of construction.

Having described my invention, what I claim therein as new and desire to secure 15 by Letters Patent is:

1. In a sanitary receptacle made of ceramic materials, the combination of a main wall, side walls made integral with and extending outwardly from said main wall, end 20 walls integral with said main and side walls and longitudinal tubular supports made integral with and supporting the junction between the main wall and the side walls.
25. 2. A sanitary receptacle made of ceramic materials comprising a main wall, side walls and end walls, all made integral with each other and tubular portions extending longitudinally of the receptacle and supporting the larger portion of the junction between 30 said main wall and side walls.

3. A urinal made of ceramic materials comprising a vertical main wall reinforced by vertical longitudinal hollow supports at each side, said supports being made integral therewith and being also formed integral with a bottom end portion and a top end portion.

4. A sanitary fixture of general rectangular box shape in character having a main wall, two side walls and two end walls and tubular column extending longitudinally of the main wall and directly connected to and made integral with both the side walls and main wall.

45 5. A sanitary fixture of general box shape in character having a main wall, two side walls and two end walls, tubular columns extending longitudinally of the main wall and directly connected to and made integral with both the side walls and main wall and a longitudinal rib extending along a central portion of and made integral with said fixture.

In testimony whereof I affix my signature.

RAYMOND E. CRANE.
